UNITED STATES PATENT OFFICE.

PETER H. POPPERT, OF DENVER, COLORADO, ASSIGNOR, BY DIRECT AND MESNE ASSIGNMENTS, TO HARRY M. ANDERSON AND CHARLES M. OSENBURG, OF SAME PLACE.

PIPE WRENCH AND CUTTER.

SPECIFICATION forming part of Letters Patent No. 630,925, dated August 15, 1899.

Application filed January 3, 1899. Serial No. 700,879. (No model.)

To all whom it may concern:

Be it known that I, PETER H. POPPERT, a citizen of the United States of America, residing at Denver, in the county of Arapahoe and State of Colorado, have invented certain new and useful Improvements in a Combined Pipe-Wrench and Pipe-Cutter; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in a combined pipe-wrench and pipe-cutter, my object being to provide a device of this class which shall be simple in construction, economical in cost, reliable, durable, and efficient in use; and to these ends the invention consists of the features, arrangements, and combinations hereinafter described and claimed, all of which will be fully understood by reference to the accompanying drawings, in which is illustrated an embodiment thereof.

In the drawings, Figure 1 is a side elevation of my improved device, the reversible jaw being arranged for pipe-cutting. Fig. 2 is a front edge view of the same. Fig. 3 is a side elevation of the tool, shown on a larger scale, the handle being broken away. In this view the reversible jaw is arranged for wrench purposes.

Similar reference characters indicating corresponding parts in these views, let the numeral 5 designate the shank of the tool, which is secured to the housing 6 by rivets 4. Through the upper part of the housing 9, above the shank, is passed the threaded portion 7^a of the jaw 7. This part 7^a also passes through a nut 8, provided with spanner-openings 8^a. The housing 6 is cut away to let in this nut and permit it to rotate.

Supported by the housing and located in the rear of the jaw 7 is the jaw 9, provided with a rotary cutter 9^a at one extremity, its opposite extremity being toothed, as shown at 9^b. This jaw 9 is provided with a slot 9^c (shown in dotted lines) and is supported in the hous-

ing by a pin 10, which passes through the slot 9^c and is fast in the housing.

The jaw 9 is adapted to slide and turn on this pin, whereby its position may be reversed to adapt it for pipe-cutting or wrench purposes, as may be desired. The rear extremity of this jaw is supported on one side by a shoulder 5^a, formed on the forward extremity of the shank 5, which projects into the housing and is shown in dotted lines. The opposite side of the reversible jaw is engaged by a pin 12, fast in the housing. When the tool is in use, the pin 10 engages the forward extremity of the slot 9^c. This pin prevents the jaw from moving backwardly during use. When it is desired to reverse the jaw or change its position from that shown in Figs. 1 and 2 to that shown in Fig. 3, the jaw 9 is first moved forward until the pin 10 engages the opposite or rear extremity of the slot 9^c. The jaw may then be reversed by turning it on the pin 10 in the direction indicated by the arrows in Fig. 1. The lower part of the housing, as well as the shoulder 5^a of the shank, is provided with a V-shaped recess, which the rotary cutter enters during the operation of reversing the position of the jaw. The tool is so constructed that the cutter end of the jaw 9 always moves down and the toothed end up when beginning the turning movement. Hence in changing the jaw from the position shown in Fig. 3 to that shown in Figs. 1 and 2 the jaw would be turned as indicated by the arrows in Fig. 3. The reason for this is that the distance is farther from the outer edge of the rotary cutter to the center of the pin 10 when the jaw is in the position shown in Figs. 1 and 2 than from the toothed edge of the jaw to the center of the same pin when the jaw is in the position shown in Fig. 3, and the construction is therefore such that more turning room is allowed the cutter end than the toothed end of the jaw.

When using the tool, the jaw 7 may be tightened upon the pipe, which is engaged on the opposite side, by either the rotary cutter or the toothed end of the reversible jaw. In tightening the jaw 7 a spanner, which engages the openings 8^a and the nut 8, may be

employed. In cutting the pipe after the jaw 7 has been properly adjusted the tool is simply turned around the pipe until it is properly cut.

5 Having thus described my invention, what I claim is—

1. The combination with a suitable supporting frame or housing, and an adjustable jaw mounted thereon, of a coöperating reversible jaw, also mounted on the frame, and arranged to turn in the plane of the adjustable jaw, whereby either extremity may be made to coöperate with the adjustable jaw as circumstances may require.

15 2. The combination with a suitable sup-

porting frame or housing and an adjustable jaw mounted thereon, of a coöperating reversible jaw, also mounted on the frame, said jaw having a slot formed therein, and a pin fast on the frame and passing through the 20 slot of the jaw, which is arranged to turn thereon, whereby either extremity may be made to coöperate with the adjustable jaw as circumstances may require.

In testimony whereof I affix my signature 25 in presence of two witnesses.

PETER H. POPPERT.
